US00D721441S

(12) **United States Design Patent**
Tipton et al.

(10) **Patent No.:** US D721,441 S
(45) **Date of Patent:** ** Jan. 20, 2015

(54) **STERILIZATION CASSETTE**

(71) Applicant: **Hu-Friedy Mfg. Co., LLC**, Chicago, IL (US)

(72) Inventors: **David W. Tipton**, Chicago, IL (US); **Timothy J. Fischer**, Chicago, IL (US); **David K. Platt**, Mount Prospect, IL (US); **Chantel D. Willis**, Munster, IN (US); **Jennifer Radovich Naylor**, Batavia, IL (US); **Marjavis J. Matthis**, Chicago, IL (US); **Mark Kurth**, Beverly Shores, IN (US); **Timothy Payne**, Chicago, IL (US); **Philip Anthony**, Chicago, IL (US)

(73) Assignee: **Hu-Friedy Mfg. Co., LLC**, Chicago, IL (US)

(**) Term: **14 Years**

(21) Appl. No.: **29/485,585**

(22) Filed: **Mar. 20, 2014**

Related U.S. Application Data

(62) Division of application No. 29/452,322, filed on Apr. 15, 2013, now Pat. No. Des. 705,442.

OTHER PUBLICATIONS

Applicant's co-pending U.S. Appl. No. 29/424,877, filed Jun. 16, 2012, entitled Sterilization Cassette, Tipton, et al.

Primary Examiner — Anhdao Doan

(74) *Attorney, Agent, or Firm* — Marshall, Gerstein & Borun LLP

(57) **CLAIM**

The ornamental design for sterilization cassette, as shown and described.

DESCRIPTION

FIG. 1 is a perspective view of the sterilization cassette of the present invention;

FIG. 2 is a front plan view of the sterilization cassette illustrated in FIG. 1;

FIG. 3 is a right side elevational view of the sterilization cassette illustrated in FIG. 1, with the left side elevational view being a mirror image thereof;

FIG. 4 is a top plan view of the sterilization cassette illustrated in FIG. 1, with the bottom view being a mirror image thereof; FIG. 5 is a perspective view of the sterilization cassette in accordance with a second embodiment of the present invention;

FIG. 6 is a front plan view of the sterilization cassette illustrated in FIG. 5;

FIG. 7 is a right side elevational view of the sterilization cassette illustrated in FIG. 5, with the left side elevational view being a mirror image thereof; and,

FIG. 8 is a top plan view of the sterilization cassette illustrated in FIG. 5, with the bottom view being a mirror image thereof. The broken lines in the drawing views are included for the purpose of illustrating portions of the sterilization cassette that form no part of the claimed design.

1 Claim, 4 Drawing Sheets
